(57) **CLAIM**

The ornamental design for a location tracking device and base charging unit, as shown and described.

DESCRIPTION

FIG. 1 is a perspective view of the front and left side of the base charging unit of the ornamental design;

FIG. 2 is a front elevational view of the base charging unit thereof;

FIG. 3 is a left side elevational view of the base charging unit thereof;

FIG. 4 is a right side elevational view of the base charging unit thereof;

FIG. 5 is a top elevational view of the base charging unit thereof;

FIG. 6 is a bottom elevational view of the base charging unit thereof;

FIG. 7 is a rear elevation view of the base charging unit thereof;

FIG. 8 is a perspective view showing the front and left side of the location tracking device inserted into the base charging unit thereof;

FIG. 9 is a perspective view showing the front and left side of the location tracking device removed from the base charging unit thereof;

FIG. 10 is a front elevational view of the location tracking device thereof;

FIG. 11 is a top elevational view of the location tracking device thereof;

FIG. 12 is a side elevational view of the location tracking device thereof;

FIG. 13 is a bottom elevational view of the location tracking device thereof; and,

FIG. 14 is a rear elevational view of the location tracking device.

The broken lines are for illustrative purposes only and form no part of the claimed design.
